UNITED STATES PATENT OFFICE.

ISIDOR M. JACOBS, OF KANSAS CITY, AND WILLIAM CRAMER, OF ST. LOUIS, MISSOURI,
ASSIGNORS TO TRUCK, TRACTOR AND MANUFACTURING COMPANY, OF ST. LOUIS,
MISSOURI, A CORPORATION OF MISSOURI.

DASHBOARD-ANCHOR FOR MOTOR-VEHICLES.

1,273,617.

Specification of Letters Patent.

Patented July 23, 1918.

Application filed November 19, 1917. Serial No. 202,726.

To all whom it may concern:

Be it known that we, ISIDOR M. JACOBS and WILLIAM CRAMER, citizens of the United States, residing, respectively, at Kansas City, in the county of Jackson and State of Missouri, and at the city of St. Louis, in the State of Missouri, have invented certain new and useful Improvements in Dashboard-Anchors for Motor-Vehicles, of which the following is a specification, reference being had therein to the accompanying drawings.

This invention, while it may be of general utility, is especially designed in aid of the salvaged constructions contemplated by the application for patent Serial Number 163,652, filed by one of the joint inventors herein named, and has for its object the ready utilization of salvaged motor vehicle parts and provides a construction whereby the seat and connected parts, such, for instance as the floor boards, dash-board, and cowl may be located at any point upon a standard or other chassis to accommodate a relatively longer or shorter salvaged engine.

This present invention is intended also as a modification of the joint invention of the same applicants for which application Serial Number 198,645 was filed on the 26th day of October, 1917.

In the accompanying drawings, in which like numbers of reference denote like parts wherever they occur.

Figure 1 is a side elevation showing part of the chassis, the hood, the seat, and the steering-post and wheel;

Fig. 2 is a sectional view on the line 2—2 of Fig. 1;

Fig. 3 is a perspective view of the seat showing its mode of attachment to the chassis; and

Fig. 4 is a perspective view of the floor-boards, dash-board, and cowl.

The chassis 1 supports the engine contained within the hood and supports also the dash-board 3 bearing the cowl 4, and likewise supports the seat 5. The steering-wheel 6 is supported by the steering-post 7, which passes through the hole 8 in the cowl 4 and connects with the front wheels of the vehicle in the usual manner.

The seat-frame rests upon the flanges 9 of the channel members forming the chassis

1, and extensions 10 of the side members 11 of the seat-supporting-frame extend along the web of the said channel members. The 55 said seat-frame may be located at any desired position in the length of the chassis.

In order to give rigidity to the side members 11 of the seat-frame and to cause the extensions 10 thereof to bear against the 60 webs of the channel members forming the chassis 1, so as to cause the seat to remain stationary at any determined spot upon the chassis 1, tie-rods 12 having at one end a bolt head and a nut 13 at the other pass 65 from the outside of one of the side members 11 to the outside of the other side member 11, and the nuts 13 tightened on the said tie-rods 12 draw the side members 11 and their extensions 10 together and into tight engagement with the chassis 1.

In the constructions contemplated by the above mentioned inventions, the salvaged or other engines used will be of greater or less length, and for this reason it is necessary 75 that the dash-board 3 shall be located farther forward or back as the case may be. This necessitates relative location of the seat 5 farther back or otherwise as made necessary by the location of the dash-board. 80 The same remarks, *mutatis mutandis*, apply to the floor-boards 14 and 15, the former of which is supported by the chassis 1 and the latter by uprights 16 attached to the chassis 1.

The gasoline tank 17 may be supported from the seat by straps 18 or other suitable means.

The steering-post 8 in the cowl can be reversed from the position shown in the 90 drawings for a left-hand drive machine to the position shown in dotted lines at 19. For this purpose it is only necessary to turn the cowl 4 around end for end. The boards 14 and 15 will preferably be supplied by the 95 dealer in the form of blanks, so as to allow the assembler to cut the same to fit the motor.

Dash-board 3 is supported from the chassis 1 by the uprights 20, preferably in 100 the shape of angle bars of which uprights 16 form a part, to which it is fastened by bolts 21 or other suitable means, and the dash-board 3 may be located at any suitable

place on the chassis 11 to accommodate the greater or less length of the engine.

With the object of keeping the dash-board 3 AND QUARTER FORWARD OF THE SAME ON THE 5 chassis from bucking when the vehicle hits a rock or rough place on the road, an L-shaped bar 26 is bolted by bolt 27 to board 23 and stayed in relation to the SAME BY 10 set-screw 28 which bears against the under- NEATH SIDE OF THE flange 9 of chassis 11. The bolt 27 passes not only through L-shaped bar 26 but also through one of the sides of angle-bar 20. A strip or washer 29 is inter- 15 posed between L-shaped bar 26 and the side of angle-bar 20. The arrangement described in this paragraph may be duplicated wherever desired or necessary on the vehicle, even upon the front side of the dash-board 3 or behind the seat or elsewhere.

Having thus described this invention, we hereby reserve the benefit of all changes in form, arrangement, order, or use of parts, as it is evident that many minor changes may be made therein without departing from the

spirit of this invention or the scope of the 25 following claims:

We claim.

1. The combination of A chassis, A dash- 30 board, A floor-board having A side member, A support for the said floor-board and for the said dash-board, an L-shaped bar, a bolt for attaching the same to the said side member, and a set-screw for staying the same relative to the flange of the said chassis;

2. The combination of a flanged chassis 35 member, a dash-board, a member having a side portion, an angle-bar fastened to the said side portion and also to the said dash- board, an L-shaped member, means for fastening the same to the said angle-member, 40 and a set-screw passing through the said L-shaped member and adapted to stay the same relative to the flange of the said chassis.

In testimony whereof we hereunto affix 45 our signatures.

ISIDOR M. JACOBS.
WILLIAM CRAMER.
